UNITED STATES PATENT OFFICE.

ALFRED L. BERNARDIN, OF EVANSVILLE, INDIANA; MARY T. BERNARDIN ADMINISTRATRIX OF SAID ALFRED L. BERNARDIN, DECEASED.

BOTTLE CAP AND METHOD OF MAKING THE SAME.

Application filed March 23, 1922. Serial No. 545,999.

To all whom it may concern:

Be it known that I, ALFRED L. BERNARDIN, a citizen of the United States, residing at Evansville, in the county of Vanderburg, 5 State of Indiana, have invented certain new and useful Improvements in Bottle Caps and Methods of Making the Same, of which the following is a description, reference being had to the accompanying drawing and to the figures of reference marked thereon.

The invention relates to new and useful improvements in bottle caps and the method of making the same.

15 An object of the invention is to provide a one piece deep drawn coated bottle cap.

A further object of the invention is to provide a bottle cap of the above type, wherein the coated surface is applied to the 20 metal in the sheet previous to drawing and wherein said bottle cap is drawn in such a way that the coated surface in the sheet forms the outer surface of the cap and so that said coating in the finished cap 25 is not appreciably disturbed.

A still further object of the invention is to provide a method of forming one piece deep drawn bottle caps, wherein the cap is formed by a progressive limited drawing contact 30 and the metal during drawing is so supported that the metal is caused to flow in the reshaping thereof to form the cap without any buckling of the metal, so that a coated surface in the sheet can form the 35 outer surface of a cap wherein the coating is not appreciably disturbed.

These and other objects will in part be obvious and will in part be hereinafter disclosed.

40 In the drawings which show by way of illustration one embodiment of the invention—

Figure 1 is a perspective view of a deep drawn one piece coated bottle cap embodying my improvements;

Fig. 2 is a vertical sectional view through the same;

Fig. 3 is a perspective view of a blank cut preparatory to the drawing of the cap;

50 Fig. 4 is a view showing the beginning of the drawing operation;

Fig. 5 is a view showing the ending of the first drawing operation;

Fig. 6 is a view showing beginning of 55 the second drawing operation;

Fig. 7 is a similar view but showing the completion of the second drawing operation.

The invention is directed broadly to a bottle cap which is formed from a single piece of metal, and which is drawn to such extent as to form what is known in the art as a deep drawn cap. The depth of the flange or body portion of the cap is at least equal to half the diameter of the cap and may be equal to or greater than the 65 diameter of the cap.

Great difficulty has been experienced in forming a deep drawn bottle cap, such as referred to above, as the strain on the metal incident to the drawing operation is distributed over such a small surface in a deep drawn cap that the flange adjacent the top portion of the cap is likely to be ruptured during drawing. Then again, in a deep drawn cap the extent of contact of 75 the dies is so great, as heretofore used, that the surface of the metal forming the outside of the cap, if lacquered or coated, is so distributed as to render the cap unsalable.

I have, however, succeeded in forming a 80 one piece deep drawn bottle cap wherein the depth of the flange is at least half the diameter of the cap or greater, and wherein the finished cap has a coating on its outer surface which is not appreciably disturbed, 85 so that the cap is readily salable. I have also been able to accomplish this result in a practical way as my improved cap has the coating applied to the sheet before the sheet is drawn to form the cap and is drawn 90 in such a way as not to appreciably disturb the coating.

The improved article will possibly be better understood by a detail description of the article and my preferred method of 95 making the same.

The improved bottle cap which I have devised consists of a top portion 1 and a body portion 2 which are formed integral. This body portion 2 is relatively deep and 100 is shown in Fig. 1 of the drawings of a depth which is slightly greater than or equal to the diameter of the cap. It will be understood, however, that I may make my cap of greater diameter than the depth 105 of the flange without departing from the spirit of the invention and still within the range of what is known as a deep drawn cap. A deep drawn cap, however, does have a flange of a depth equal to or greater 110

than half the diameter of the cap. Said cap is preferably provided with vertically extending corrugations 3, often referred to as a knurl, to aid in turning the cap on to the bottle or jar. The cap is also provided, as shown in the drawings, with a thread 4 which is adapted to engage the thread on the bottle, and the cap which I have shown is known in the art as a screw cap. It will 10 be understood, of course, that lugs may be used in place of the thread, or any other means of shaping the cap to hold it on the bottle or jar.

My improved cap is formed from a sheet 15 of metal which is first coated. In Fig. 3 of the drawings, I have shown a blank 5, the upper surface of which is provided with a coating 6. This coating may be of lacquer or enamel, lithographed, or decorated in any 20 desired way, and it is to be understood that, by the use of the term "coating" I intend to cover all various known ways of covering the metal for protection, or for the purpose of decorating, but I do not contemplate by 25 this expression the initial tinning of a sheet of steel to form tin plate. My improved cap is made of metal, and preferably tin plate, although of course other metals may be used without departing from the spirit 30 of the invention as set forth in the claims.

The sheet after being coated is cut into blanks, each one of which forms a cap. The blank is preferably cut at the time when the blank is to be drawn so as to avoid handling 35 separate blanks. A blank is placed in a machine which is provided with a female die 7 and a male die 8. This female die 7 is formed with a drawing ring 9, which has a curved drawing face 10. As clearly shown 40 in the drawings, the depth of the ring is very much less than the depth of the flange of the cap to be drawn. The die above the drawing ring is of larger diameter than the drawing ring. The metal is placed across 45 the entrance to the female die and is yieldingly clamped against the drawing ring by a spring supported clamping ring 11. The male die is forced upwardly or the female die forced downwardly so as to give a relative movement to the die members and the 50 metal is thus drawn into cap form. In Fig. 4 of the drawings, I have shown the male die just entering the drawing ring and the metal as having been started on the reshaping of the same to form the cap. It 55 will be noted that the drawing ring makes contact with the metal at the portion thereof which is to form the top of the cap and this drawing ring has a progressive movement 60 along the flange or body portion of the cap to the extreme lower edge thereof during drawing. As above noted, the drawing contact between the ring and the flange of the cap is very limited. Two very important results are accomplished by this

limited drawing contact. In the first place, the strain incident to the drawing is reduced to a minimum and this enables me to produce a relatively long drawn flange in one operation. As a matter of fact, where 70 the flange is only about equal to one half of the diameter of the finished cap, I may draw the cap in one operation. However, when the depth of the flange is approximately equal to the diameter of the cap, then 75 I use two drawing operations as the strain would be so great of the male member 8 of the die, on the relatively small top portion 1 of the cap, as to rupture the metal if the drawing operation were so extensive. 80

In Fig. 5 of the drawing, I have shown what may be used as a cap where the depth of the flange is approximately one-half the diameter of the cap and what may be used as the shell for the second drawing operation where the depth of the flange is to be greater than one-half the diameter of the cap. 85

The second result accomplished by this relatively narrow drawing contact is that 90 the coated surface is subjected to a minimum amount of frictional slipping contact, so that the coated surface is not appreciably disturbed during the drawing operation. The pressing ring supports the metal and 95 prevents the same from wrinkling or bending so that during the drawing of the cap the metal flows for a reshaping of the blank to form the cap as distinguished from any bending of the metal. When the cap is 100 subjected to a second drawing operation it is placed in a die, such as shown in Fig. 6. The female die is provided with a drawing ring 13, which has a limited drawing contact on the metal similar to that described 105 above in connection with the dies in Figs. 4 and 5. Associated with the female die is a supporting sleeve 14 which is of the size of the initially drawn shell, so that the shell slips down over this sleeve. The upper end 110 of this sleeve is shaped to conform with the shell so as to completely support the metal on the inside of the shell. This together with the shaping of the drawing ring which is curved and tapered, forms a drawing 115 throat which is gently curved so that the metal may flow through the throat into the reshaped condition to form the cap and be supported so as to insure a flowing of the metal as distinguished from a bending of 120 the metal. The male die member 15 works through the sleeve 14 and operates to bring about a drawing of the cap.

In the second drawing operation I employ 125 the same members as have been described above. The metal is clamped or supported on both sides thereof so as to prevent wrinkling or bending and is drawn by a drawing ring having a very limited drawing contact of much less extent than the depth of the 130

flange, which reduces the strain incident to drawing and which also limits the extent of contact between the drawing ring and the surface of the cap; this drawing contact 5 beginning at the top of the cap and progressing or moving downwardly to the edge of the cap. By this limited contact I am able to put the coated shell through a second drawing operation without appreciably 10 disturbing the coating thereon.

From the above, it will be apparent that I have provided a one piece deep drawn coated bottle cap, wherein the coating is applied to the metal in the sheet previous 15 to drawing and, therefore, can be evenly applied and after the metal has been coated it is drawn into the form of the cap without disturbing appreciably the coating thereon. The cap after it is drawn is knurled and 20 threaded and then trimmed at the lower edge thereof, which finishes the cap. The trimmed edge may be left free; as shown in the drawings, or it may be curled.

It will be understood, of course, that the 25 inside of the cap may be lacquered and the lacquer applied to the metal in the sheet. I have described in detail the outer coating as this is the coating that is likely to be rubbed or marred during drawing. I do 30 not claim broadly a new method of drawing metal, but my invention resides in the method of forming a deep drawn bottle cap.

It is obvious that minor changes in the 35 shaping of the parts and the proportions thereof may be made without departing from the spirit of the invention as set forth in the appended claims.

Having thus described my invention, what I claim as new and desire to secure 40 by Letters Patent, is:

1. As an article of manufacture, a one-piece deep drawn bottle cap having its outer

surface provided with a coating of such a character as would be injured or disturbed by the usual methods of deep drawing, comprising an integral top and a seamless body portion having a depth equal to at least one-half the diameter of the cap, said cap being formed from a blank cut from a coated sheet and by a drawing contact beginning with 45 the blank in flat condition and at the portion of the blank which is to form the top of the cap and progressing toward the edge of the cap whereby the re-shaping of the metal to form the cap is secured by a flowing of the 50 metal without any substantial bending or buckling thereof and the coating applied in the sheet is thereby unappreciably disturbed during the forming of the cap.

2. The method of forming a one-piece 60 deep drawn bottle cap having on its outer surface a coating of such a character as would be injured or disturbed by the usual methods of deep drawing, comprising coating the metal from which the cap is to be 65 formed in the sheet, cutting a blank from the sheet, drawing the cap from the blank by a drawing contact beginning with the blank in flat condition and at the portion which is to form the top of the cap and 70 progressing toward the edge of the cap, said drawing contact being limited to a small portion of the depth of the cap whereby the drawing strain is reduced to a minimum and supporting the metal during drawing so 75 that the entire re-shaping of the metal is secured by a flowing of the metal without any substantial bending or buckling thereof whereby the coating applied in the sheet is unappreciably disturbed during the forma- 80 tion of the cap.

In testimony whereof, I affix my signature.

ALFRED L. BERNARDIN.
